UNITED STATES PATENT OFFICE

2,574,035

AUTOMATIC RAFTER SQUARE

Herbert Cowan Heiskell, Joplin, Mo.

Application January 31, 1951, Serial No. 208,710

3 Claims. (Cl. 33—95)

1

This invention relates to a rafter square. More particularly, the invention has reference to a rafter square of novel design, embodying an adjustable ruling blade which, when adjusted to the selected position, permits all necessary cuts to be made upon the rafters with ease and speed, with only one adjustment for both cuts of the rafter.

One important object of the present invention is to provide a rafter square of the character described which will, when set, be automatically adjusted for proper marking and cutting of rafters to selected angles, without the necessity of the user knowing any more, in advance, than the width of the house and the desired rise to be given to the rafters.

Another important object is to provide a device of the character described the setting of which can be effected simply, quickly, and with complete accuracy. No computations are necessary, since the length of the rafter is given automatically.

Another important object is to provide a device as stated which is readily usable by unskilled laborers.

Still another object is to provide a tool as stated which can be manufactured at relatively low cost, and which will be durable and so formed as not to readily get out of order.

With the foregoing and other objects in view which will appear as the description proceeds, the invention consists of certain novel details of construction and combinations of parts, herein-after more fully described and pointed out in the claims, it being understood that changes may be made in the material and construction and arrangement of parts without departing from the spirit of the invention as claimed.

Referring to the drawings

Fig. 1 is a top plan view of a rafter square formed in accordance with the present invention.

Fig. 2 is an enlarged top plan view of a fragmentary portion of one arm of the square.

Fig. 3 is a longitudinal section through said fragmentary portion of the arm.

Fig. 4 is an enlarged section on line 4—4 of Fig. 1.

Fig. 5 is a view similar to Fig. 1 on a reduced scale, showing a second position of the rule, portions of the rule being broken away.

Fig. 6 is an inverted perspective view of one of the guides mounted on the rule.

Referring to the drawings in detail, the rafter square constituting the present invention embodies a conventionally formed square including the rigidly connected arms 1 and 2 at right angles

2

to each other, said square being graduated along its outer edge in twelfths of an inch.

Mounted upon the arm 1 is a flat sleeve 3 slideable upon the arm, thus having the plates 4 rigidly connected to said sleeve in spaced relation, each plate 4 being formed with an upstanding bracket 5. The brackets have arcuate slots 6 for a purpose to be made apparent.

In the space between the brackets is disposed 10 one end of a solid or channeled lock member 7 pivotally connected to the brackets as at 8. The member is shown as channeled in the present instance, but it could be solid if so desired. Said end of the lock member 7 is provided with a cam 15 surface 9.

The lock member 7 overlies a locking bar 10 rigidly connected by rivets 11 to the flat sleeve 12 also slideable upon the arm 1. A spacer plate 13 is interposed between the locking bar 10 and the sleeve 12.

Centrally of the locking bar 10, there is formed therein a pin-receiving opening 13', and at its other or free end there is another pin-receiving opening 14 receiving the L-shaped pin 15 that extends through the slots 6.

The lock member 7, when adjusted to one position, allows the locking bar 10 to spring upwardly at its free end. This releases, for adjustment relative to the square arm 1, one end portion of a ruling blade 16 one longitudinal edge of which may be reinforced by a channeled member 17. The ruling blade 16 is of transparent plastic material.

As will be noted, the other end portion of the 35 ruling blade underlies another locking bar 18 formed like the locking bar 10. The bar 18 is rigidly secured at one end to a sleeve 19 slideable upon the arm 2, and the other end of the bar 18 springs upwardly between brackets 20 mounted upon a sleeve 20' slideable upon the arm 2.

A solid or channeled cam type locking member 21, operating similarly to the member 7, is pivotally connected to and between the brackets 20, and controls the bar 18 in the same manner that the member 7 controls the bar 10.

An L-shaped pin 22 is insertible in an opening 22' formed adjacent the free end of the bar 18, said opening corresponding to the opening 14 of the bar 10. Alternatively, the pin 22 is insertible in an intermediate opening 23 corresponding to opening 13.

In use, the pins 15 and 22 can be positioned either in the center openings 13' and 23, or in the end openings 14 and 22'. In the centered 55 position of the bars 10 and 18 it becomes possible

to make use of the corner of the square. The cam lock members 7 and 21 are now swung upwardly so as to permit upward swinging of the free ends of the bars 10 and 18. This increases the space between said bars and the square arms 1 and 2 and permits free adjustment of the ruling blade 16, which in effect has a floating mounting upon the arms 1 and 2.

After the end portions of the ruling blade have been adjusted to a desired position, the cam lock members 7 and 21 are swung downwardly, causing the members 18 and 10 to be pressed downwardly toward the arms 1 and 2, thus to engage the end portions of the ruling blade 16 and hold said ruling blade in a selected position of adjustment.

There is no possibility of the end portions of the ruling blade slipping out of a desired location of adjustment, as the cams prevent movement of the slides that slide on both arms of the steel square. The transparent rule when forced against the respective arms of the square, and fixed in proper position for any certain pitch of rafter, remains accurate.

Thus, it may be noted that assuming that the square is marked in twelfths, the length and angle of the rafters is automatically determined by merely setting the plastic rule.

Thereafter, the ruling blade will, when it is positioned against the steel square and the bars 18 and 10, be automatically set for the particular angle of rafters to be cut, and the rafters can be marked and cut as desired, with but this one adjustment.

The ruling blade is provided with a pair of slideable sleeve guides 24 at opposite ends. These are placed on both ends or in the middle of the plastic rule, depending flanges 25 engageable against the same sides of a length of wood to be marked. When the ruling blade is in the position of Fig. 1, the guides can if desired be used on the center portion of the ruling blade.

With further reference to the ruling blade, this is provided with parallel line markings 26, 27, 28, 29 and 30. These lines provide the length at the ridge cut from heel to comb for rafters of various sizes. Thus, line 26 refers to 2" x 12" lumber; line 27 refers to 2" x 10" lumber; line 28 refers to 2" x 8" lumber; line 29 refers to 2" x 6" lumber; and line 30 refers to 2" x 4" lumber.

The ruling blade, further, is graduated by transverse lines as at 31, there being twenty-four said lines to each inch.

What is claimed is:

1. A rafter square including a square member including rigidly connected arms at right angles to each other, a ruling blade extending angularly across said arms and having a floating mounting upon said arms, slide members slideable along the respective arms, locking bars mounted upon the slide members, and means for pressing

the locking bars against the respective end portions of the ruling blade to hold the ruling blade in selected positions to which it is adjusted.

2. A rafter square including a square member having arms rigidly connected and disposed at right angles to each other, a pair of sleeves mounted for sliding movement upon each of said arms, a locking bar loosely connected at one end to one sleeve of a pair of sleeves, the other ends of the locking bars having a solid riveted connection to the other sleeves of the respective pairs of sleeves, said other loose ends of the locking bars adapted to swing upwardly, lock members mounted upon certain of said sleeves above the feed ends of said locking bars, said lock members adapted to force the locking bars downwardly against the spring action thereof, and a ruling blade having a floating mounting beneath the respective arms, said ruling blade having end portions underlying the respective bars and locked by the locking bars, said end portions of the ruling blade being adapted to be engaged between the locking bars and the arms of the square member to clamp the end portions of the ruling blade in selected positions.

3. A rafter square including a pair of arms rigidly connected at right angles to each other, a pair of sleeves slideable upon each of said arms, a locking bar rigidly connected at one end to one sleeve of each pair of sleeves, the other end of each locking bar being springable upwardly above the other sleeve of each pair of sleeves, said locking bars having openings intermediate their ends and at their ends, a pin insertable in said openings and constituting a stop pin, a transparent ruling blade under said locking bars floating or movable upon the respective arms, and a solid or channeled locking member pivotally connected to one sleeve of each pair of sleeves above the free end of the locking bar, said channeled locking member having a cam surface at one end, said cam surface being adapted to engage the free end of each locking bar to force said locking bar downwardly in the direction of the arm underlying the locking bar, thus to clamp the end portions of the ruling blade in selected positions of adjustment upon the arms, said pins constituting stops changing said positions of sleeves to make use of corner of square by clamping ruling blade with end instead of center of locking bar.
